UNITED STATES PATENT OFFICE.

NOAH S. HARTER, OF WAUKEGAN, ILLINOIS, ASSIGNOR TO AMERICAN STEEL & WIRE COMPANY, OF CHICAGO, ILLINOIS, A CORPORATION OF NEW JERSEY.

METHOD OF MAKING COIL-SPRINGS.

No. 873,429.

Specification of Letters Patent.

Patented Dec. 10, 1907.

Application filed May 6, 1907. Serial No. 372,005.

To all whom it may concern:

Be it known that I, NOAH S. HARTER, of Waukegan, Lake county, Illinois, have invented a new and useful Method of Making 5 Coil-Springs, of which the following is a full, clear, and exact description, reference being had to the accompanying drawing, forming part of this specification, in which the figure is a perspective view illustrating one form of 10 apparatus for carrying out my invention.

In the manufacture of open coil springs heretofore, it has been the practice to press the coils together after the spring has been wound or coiled for the purpose of giving the 15 spring a permanent set. A spring coiled in the ordinary manner will not resume its original length after it has been compressed to its minimum length, but will be materially decreased in both pitch and length by such 20 compression. This decrease constitutes the "set" of the spring; and after this has once been effected, the spring when subsequently compressed will, when released, resume approximately the length and pitch effected by 25 the first compression or set.

The object of the present invention is to provide a method whereby the springs are given a set at the time they are wound or coiled, or as they pass out from the coiling 30 mechanism.

The invention may be carried out in various ways and by the use of various forms of coiling mechanisms. In the accompanying drawing, I have illustrated one way of performing 35 the same.

In this drawing, the numerals 2 and 3 designate a pair of peripherally grooved feed wheels, which may be driven in any desired manner. The upper wheel 2 is preferably 40 mounted in an adjustable bearing 4, having an adjustable setting screw 5 by means of which its position relative to the wheel 3 may be adjusted to regulate the feeding pressure of said wheels. From these wheels, 45 the wire passes through any suitable guide 6, and is coiled on the arbor or mandrel 7. The wire, being tightly clamped between the wheels 2 and 3, is forced through the guide 6 and around the arbor or mandrel, being 50 assisted by the guiding surface 6^a below and adjacent to the mandrel.

8 designates a suitable tool which is adjustably secured in a support 9, and which has a beveled nose 10 adjacent to the arbor in position to guide the wire to the same. This 55 tool governs the pitch of the spring; and by turning it in its support 9 to vary the angle of the guiding face of its nose 10, the pitch may be changed as desired. 11 designates a second tool, also adjustably secured in the support 9, and having a nose portion 12 which is adjacent to the nose 10, and in position to bear against the outer side of the second turn or coil of wire on the arbor and press said coil back closely against the first coil, thereby 60 imparting a set to said second coil. In this manner, each coil is successively given a set after it is wound. By this method, I eliminate one operation and also the handling 65 consequent thereto, it having been the practice heretofore to coil the springs on one machine, and then transfer them to another where the set is given.

My invention is applicable to the manufacture of all kinds of open-coil springs 75 whether of the spiral type, or of the furniture spring type, and may be carried out with various forms of apparatus.

What I claim is:

1. The method of forming helical springs, 80 which consists in forming wire into a series of coils, imparting to each coil as it is formed a pitch in excess of the desired pitch, and then pressing each coil backwardly against the following coil to remove the excess pitch and 85 give a permanent set thereto; substantially as described.

2. The herein described method of forming open coil springs, which consists in winding or coiling a piece of wire to form coils of a certain pitch, and pressing each coil backwardly 90 against a later coil to remove excess pitch and give a permanent set; substantially as described.

In testimony whereof, I have hereunto set 95 my hand.

NOAH S. HARTER.
